DESIGN FOR AN ENSEMBLE DRESS

Emil Schwartz, New York, N. Y.

Application November 8, 1935, Serial No. 59,442

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The horizontal and vertical lines on the cuff of the jacket, and on the yoke portion of the dress, represent latticework.

I claim:

The ornamental design for an ensemble dress, substantially as shown, and described.

EMIL SCHWARTZ.
